UNITED STATES PATENT OFFICE.

HERMAN SOMERFLECK, OF BROOKLYN, NEW YORK.

DESIGN FOR A HANDLE.

Application filed June 29, 1923. Serial No. 6,626. Term of patent 3½ years.

To all whom it may concern:

Be it known that I, HERMAN SOMERFLECK, a citizen of the United States, residing at New York, borough of Brooklyn, in the county of Kings and State of New York, have invented a new, original, and ornamental Design for Handles, of which the following is a specification, reference being had to the accompanying drawing, forming part thereof, wherein the figure is a perspective view of a handle, showing my new design.

I claim:

The ornamental design for a handle as shown.

Signed at New York, borough of Manhattan, in the county of New York and State of New York, this 27 day of June, 1923, before two subscribing witnesses.

HERMAN SOMERFLECK.

Witnesses:

WILBUR M. STONE,
WILBUR C. ABBOTT.
